UNITED STATES PATENT OFFICE.

GEORGE HOWLETT DAVIS, OF WEST ORANGE, NEW JERSEY, AND CHARLES T. BOWMAN, OF SCHENECTADY, NEW YORK, ASSIGNORS TO STANDARD MUSIC ROLL COMPANY, A CORPORATION OF NEW JERSEY.

PATTERN-CONTROLLED PUNCH-SELECTING PERFORATING-MACHINE.

No. 900,151.

Specification of Letters Patent.

Patented Oct. 6, 1908.

Application filed December 10, 1906. Serial No. 347,231.

To all whom it may concern:

Be it known that we, GEORGE HOWLETT DAVIS and CHARLES T. BOWMAN, citizens of the United States, residing at West Orange, 5 in the county of Essex, State of New Jersey, and Schenectady, county of Schenectady, State of New York, respectively, have invented new and useful Improvements in Pattern-Controlled Punch-Selecting Perforating-Machines, of which the following is a specification.

The present invention relates to what is known in the art as pattern controlled punch selecting perforating machines, such, for instance, as are designed or employed for punching note perforations in strips or webs of paper for use in connection with self-playing musical instruments.

The improvements sought to be protected 20 relate more particularly to the punch selecting mechanism or reader designed to control the locking or setting of the appropriate punch or punches to produce an exact copy of the pattern. The said reader or punch 25 selecting mechanism is shown in the present instance as associated with a well known form of perforating mechanism, such, for instance, as shown in the prior patent to Geo. Howlett Davis, 659,053, October 2, 30 1900, but it will be understood that the said reader or selecting mechanism may be associated with other forms of perforating mechanism of the punch selecting type.

The prime object sought to be obtained by 35 the present invention is to insure a true and accurate copy of the pattern, not only with respect to the long note perforations, but more especially as to very short or single perforations representing the shortest notes.

In prior constructions great difficulty has 40 been encountered in reproducing truly and accurately the composition of the pattern which is due to a "skipping" or "missing" of the small perforations in the pattern occasioned by an irregular or out of phase feed of 45 the pattern, relatively to the feed of the paper to be perforated. In other words, in perforating machines of the pattern controlled punch selecting type, the paper to be 50 punched and the pattern are usually caused to travel in synchronism step by step. It sometimes happens that during the feeding of the pattern sheet over the readers or

punch selectors that the step feeding movement of the pattern causes the latter "to jump" a particular reader element or reader elements without giving said element or elements an opportunity to perform the required work and this is especially true with respect to very short perforations in the pattern. Obviously this results in an inaccurate reproduction of the pattern and oftentimes renders the perforated sheet or sheets fatally defective.

The prime purpose of the present invention 65 is to overcome the above noted objections and this is accomplished by providing means whereby a relative longitudinal adjustment may be given between the reader elements and the pattern or pattern feeding means so as to 70 insure a positive and accurate operation of the readers with respect to any and all of the perforations in the pattern, irrespective of the size thereof, the said relative adjustment between the parts referred to, in the present 75 instance, being manually controlled, although it is not desired to limit the invention to a manually controlled means; neither is it desired to limit the invention to electrically controlled selectors or readers for obviously 80 the improvements may be applied to other forms of mechanism.

The invention has in view other more or less important features of construction as will more clearly hereinafter appear in the 85 detailed description to follow.

In the annexed drawings showing one embodiment of the invention. Figure 1 represents in perspective view a perforating machine of the well known Davis type heretofore referred to showing the actuating means for imparting a step by step feed movement to the pattern. Fig. 2 is a detailed end view partly in section and partly in side elevation of two of the relay magnets. Fig. 3 is a vertical sectional view of the perforating machine and its operative connections with the pattern operating and controlling mechanism, a portion only of the latter of which is shown. Fig. 4 is a top plan view of the pattern controlling mechanism and readers or selectors. Fig. 5 is a vertical sectional view taken on the line 5—5 of Fig. 4. Fig. 6 is a detailed perspective view of several of the reader elements or selector fingers and their 100 circuit connections. Fig. 7 is a diagram-

matic view of the circuits leading from the reader or note selecting elements to the punch selecting magnets. Fig. 8 is an enlarged detailed sectional view of the reader 5 elements or punch selectors.

As before stated the present invention is shown associated with the well known Davis type of perforating machine fully shown and described in the prior patent referred to, and 10 it is not deemed necessary, therefore, to enter into a detailed description of this part of the machine. For the sake of clearness, however, some of the main parts of the machine will be described in a general way.

15 Referring to Fig. 1, the reference numeral 1 designates the bed of the machine having two standards 2, rising from opposite sides thereof in each of which reciprocates a slide block 3. These slide blocks are reciprocated 20 by means of pitmen arms 4 each connected at its lower end to one of the slide blocks 3 and at its upper end to an eccentric 5 secured to a driving shaft 6 that is journaled in bearings in the standards 2. The shaft 6 is rotated 25 from any suitable source of power through the medium of a pulley 7 fixed on said shaft. A clutch sleeve 8 slidable on said shaft is arranged to engage when desired, the clutch element 9 on the pulley 7 to stop and start 30 the machine. The clutch sleeve 8 is shifted laterally into and out of engagement with the clutch element 9 by means of a lever 10 pivoted at 11, and having a rod connection 12 at its free end with a treadle 13. A 35 spring 14 attached at one end to said lever and at its other end to the bed plate of the machine is employed to normally hold the clutch sleeve 8 out of engagement with the clutch element 9. The slide blocks 3 loosely 40 carry a plurality of punches 15 the lower ends of which pass through a perforated die block 16 below which is mounted a die plate 17. A space is left between the die block and the die plate through which passes the sheets or 45 webs to be perforated, it being understood that in machines of this type a number of sheets or webs are perforated at a single operation. The punches 15 are locked for operation by means of locking dogs 18 pivoted 50 at 19 to a transverse bar 20 carried by the slide blocks. The punch locking dogs 18 are drawn into position to lock the punches 15 by means of rod connections 21 with the armatures 22 of electro-magnets 23 all as 55 more clearly shown in Fig. 7, the said magnets being of the current saving type shown in the aforesaid Davis patent and arranged in circuit with relays 24 which magnets and relays are designed to save current and reduce sparking at the readers or punch selecting fingers.

In the operation of the machine as the pattern sheet passes between the reader elements, presently to be described, the said elements 65 find their way through the perforations in

the pattern and complete the electric circuit through the punch selecting magnets 23 causing an attraction of the armatures 22 and through the rod connections 21 move the punch selecting dogs in position to lock the 70 punches 15 in position to cause them to pass through the paper to be perforated, which paper is represented by the reference numeral 25.

Having briefly described the perforating 75 machine the reader mechanism and its advantages will now be set forth.

The reference numeral 26 designates a base plate having fixed thereto a pair of guide-ways 27 between which is slidably and 80 adjustably mounted the reader frame or support comprising a transverse bar or rail 28 having a base plate 29 guided between the guide-ways 27 and having depending therefrom a lug 30 provided with a screw-threaded 85 aperture in which works a screw 31. This screw 31 has fixed to one end thereof, a beveled gear 32 meshing with a beveled pinion 33 the latter being fixed to a shaft 34 having at its free end a manually operable 90 knurled head 35.

It will be apparent from the foregoing that an operation of the shaft 34 through finger engagement of the operator with the knurled nut 35 will cause a rotation of the threaded 95 shaft 31 which will result in a movement of the reader rail 28 either forward or backward, depending upon the direction of movement given the shaft 34, the purpose of which will be presently explained in detail. The 100 upper end of the rail 28 is channeled as more clearly shown in Fig. 5 and in the said channeled portion is arranged a tracker bar 36 carrying a vertically adjustable contact member 37, said member being mounted in a 105 channel 38 in the tracker bar and made adjustable by two set screws 39 as more clearly shown in Fig. 8. Pivotally connected to opposite ends of the rail 28 is a pair of arms 40 having attached thereto, at their free ends, a 110 transverse bar 41 carrying a rail of insulating material 42 through which passes a plurality of selector fingers or readers 43 the free end of each one of which projects rearwardly and enters the notched or bifurcated end 44 of a 115 contact plate 45 to which the circuit wires 46, Fig. 7, leading to the several electro-magnets 23 connect. These plates 45, of which there is one for each selector finger are attached to a strip of insulated material 47 carried by an angle rail 48, said rail being attached to the bar 41 as more clearly shown in Fig. 5. The separate circuit wires 46 leading from the plates 45 form a cable 49 seated between the walls of the angle rail 48 as more 120 clearly shown in Figs. 4 and 5.

By the construction described it will be seen that a readily detachable connection is provided between the selector fingers 43 and the plates 45 with which the circuit wires 46 130

connect so that in case any of said fingers become broken or deranged a new finger can be easily substituted. The bar or rail 41, to which the selector fingers 43 are connected 5 through the medium of the rail of insulating material 42 is pivotally connected between the arms 40, said pivotal connection being made through the shaft 50 to the outer end of which is fixed an arm 51 that is normally drawn down by means of a coiled spring 52 by which arrangement the selector fingers 43 are caused to bear down toward the contact member 37 with a yielding pressure.

By referring to Fig. 8 it will be seen that 15 the contact member 37 is vertically adjustable in the channel 38 of the tracker bar 36 so that the upper face thereof may be adjusted relative to the upper face 53 of the said tracker bar 36 so as to leave an air gap 20 or space between the selector fingers and the said contact member 37 in order to prevent false circuit which would occur if the pattern 54 should contain a metallic particle.

Rising from the bed plate 26 are two pairs 25 of standards 55 and 56 the latter of which is provided with end bearings 57 to receive a delivery spool 58 carrying the pattern 54, the said standards also carrying a guide roller 59 over which the pattern passes on 30 its way to the readers or selector fingers. Journaled in the standards 55 at the lower end of the base plate 26 is a take-up roll 60 to which the free end of the pattern 54 is attached and also journaled in said standards 35 is a pair of feed rolls 61, 62 having intermeshing gears 64 and between which the pattern passes on its way to the take-up roll 60. A friction roll 65 journaled in the standards 55 is disposed adjacent to the feed roll 40 62. On the outer end of the shaft carrying the feed roll 62 is a ratchet wheel 66 to which a step-by-step rotary feed is imparted through the medium of a pawl 67 attached to a rocker arm 68 to the lower end of which 45 is connected a reciprocatory rod 69, said rod being connected to an arm 70 attached to a rock shaft 71 journaled in a forked bracket 72, secured to the bed plate 1 of the perforating machine. The rock shaft 71 is 50 further provided with an upstanding arm 73 that is positioned to be engaged by a cam 74 mounted on the outer end of the driving shaft 6 of the perforating machine, said cam 74 being provided with a groove 75 55 with which the upstanding arm 73 aligns. The rocker arm 68 is normally drawn forward by means of a spring 76 attached to a bracket 77 secured to the base plate 26 and movement in the opposite direction is effected by means of the cam 74 through the 60 operative connections already described. A back lash pawl 78 pivoted to one of the standards 55 is normally in engagement with the ratchet wheel 66 to prevent backward movement thereof.

From the construction described it will be seen that a rotation of the main shaft 6 of the perforating machine causes through the connections described, a step-by-step feed movement to be imparted to the feed 70 rolls 61-62 causing the pattern to be drawn in a step-by-step manner between the members of the punch selectors or readers causing the latter, as the perforations appear between them to complete the 75 circuits through the magnets 23 and set the punch dogs and punches for operation.

As before pointed out it sometimes occurs, during the step-by-step movement of the pattern sheet, that when very short perforations appear in the pattern, a skipping or jumping of the same will occur, owing to the fact that as a result of the previous step movement the selector finger will rest or stop immediately at the edge of the perforation so that during the next step movement of the pattern, the perforation will move entirely through and across the two members of the reader elements without giving these elements an opportunity to enter the perforation and accomplish their work. To obviate this difficulty and to insure an accurate entry of the selector finger or fingers into the punch opening or openings in the pattern, no matter how small, the means 95 herein described have been employed to cause a relative longitudinal adjustment between the readers and the traveling sheet or web so that during the operation of the machine, if the operator who is in attendance 100 should discover that any one or more of the perforations in the pattern stopped too close to the end of a selector finger or fingers to cause said operator to believe that the next step movement would carry the perforation 105 entirely across and through the reader elements he would simply, by a proper manipulation of the knurled nut 35 and its connections with the screw 31, cause the rail 28 and with it the entire reader mechanism to 110 be moved forward or backward in the line of feed of the pattern so as to bring the selector finger 43 in proper position to insure their entry into the perforations. It will be understood, of course, that only a very slight movement will be required to effect 115 the required adjustment, as the step feed is a short one. This adjustment of the reader mechanism in the embodiment of the invention shown herein is controlled manually by 120 the operator, and may be accomplished while the machine is in operation, or the machine may first be stopped by shifting the clutch elements 8 and 9 through the treadle 13 and its operative connections.

By the means described or any equivalent means, wherein there may be had a relative longitudinal adjustment between the sheet or web or its carrying mechanism and the readers, it will be apparent that one or the other 130

of these elements may be moved at will to insure a proper completion of the circuit or circuits leading to the punch locking dogs, so that a true and accurate copy of the pattern 5 as to all perforations may be had. It is also possible with the construction shown, to feed the pattern forward, one or more step movements, independent of the movement of the sheets being punched, whereby any inaccuracies 10 occurring in the pattern may be corrected. This result is accomplished manually by the operator, who first stops the operation of the punching mechanism by depressing the foot treadle to shift the clutch member 8, out 15 of contact with the member 9, and then manually operates the rod 69, or one of the arms 73 or 75 on the rock shaft 71, to rotate the ratchet wheel 66, and with it the pattern feed rolls 61, 62, to feed the pattern sheet forward 20 one or more steps as desired. Inasmuch as there is no direct connection between the pattern feeding-means and the power shaft of the punching machine, it is apparent that the ratchet wheel 66, may be rotated at will in- 25 dependently of the said power shaft.

What we claim and desire to secure by Letters Patent is:—

1. In a pattern controlled punch selecting perforating machine, and in combination, 30 perforating mechanism, a reader adapted to coöperate with a pattern to control the operation of the perforating mechanism, and means for effecting a relative longitudinal adjustment between the reader and pattern.

35 2. In a pattern controlled punch selecting perforating machine, and in combination, perforating mechanism, a reader, a pattern sheet support, and means for effecting a relative longitudinal adjustment between the 40 reader and pattern sheet support.

3. In a pattern controlled punch selecting perforating machine, and in combination, perforating mechanism, a reader, a pattern sheet, feeding means and means independent 45 of the feeding means for effecting a relative longitudinal adjustment between the reader and pattern sheet feeding means.

4. In a pattern controlled punch selecting perforating machine, and in combination, 50 perforating mechanism, a reader adapted to coöperate with a pattern sheet to control the operation of the perforating mechanism, and manually operable means for effecting a relative longitudinal adjustment between the 55 reader and pattern sheet.

5. In a pattern controlled punch selecting perforating machine, and in combination, perforating mechanism, a reader, a pattern sheet holder, and manually operable means for effecting a relative longitudinal adjustment between the reader and pattern sheet support.

6. In a pattern controlled punch selecting perforating machine, and in combination, perforating mechanism, a reader comprising two 65 coöperating elements, between which a pat-

tern sheet is adapted to pass, and means for effecting a relative longitudinal adjustment between the reader and pattern sheet.

7. In a pattern controlled punch selecting perforating machine, and in combination, perforating mechanism, a reader comprising two coöperating electric contact members, between which a pattern sheet is adapted to pass, and means for effecting a relative longitudinal adjustment between the reader and 75 pattern sheet.

8. In a pattern controlled punch selecting perforating machine, and in combination, perforating mechanism, a reader adapted to co-operate with a pattern sheet, and means for 80 adjusting the reader longitudinal relatively to the pattern sheet.

9. In a pattern controlled punch selecting perforating machine, and in combination, perforating mechanism, a reader adapted to co-operate with a pattern sheet, and manually operable means for adjusting the reader longitudinal relatively to the pattern sheet.

10. In a pattern controlled punch selecting perforating machine, and in combination, perforating mechanism, a reader adapted to co-operate with a pattern sheet and means for 90 adjusting the reader in the line of movement of the pattern sheet.

11. In a pattern controlled punch selecting perforating machine, and in combination, perforating mechanism, a reader adapted to co-operate with a pattern sheet, and manually operable means for adjusting the reader in 95 the line of movement of the pattern sheet. 100

12. In a pattern controlled punch selecting perforating machine, and in combination, perforating mechanism, a reader adapted to co-operate with a pattern sheet, means for imparting a step-by-step movement to the pattern sheet, and means for effecting a relative longitudinal adjustment between the reader and pattern sheet.

13. In a pattern controlled punch selecting perforating machine, a perforating mechanism, a reader, adapted to coöperate with a pattern sheet to control the operation of the perforating mechanism, means operated by the perforating mechanism for imparting a step-by-step feed movement to the pattern sheet, and means for effecting a relative longitudinal adjustment between the reader and pattern sheet without affecting the initial feed of the latter.

14. In a pattern controlled punch selecting perforating machine, a perforating mechanism, a reader, adapted to coöperate with a pattern sheet to control the operation of the perforating mechanism, means operated by the perforating mechanism for imparting a feed movement to the pattern sheet, and means independent of the feeding means for effecting a relative longitudinal adjustment between the reader and pattern sheet.

15. In a pattern controlled punch selecting 130

perforating machine, a perforating mechanism, a reader, a coöperating pattern, means operated by the punching mechanism for imparting a step-by-step feed movement to the pattern and manually operable means for effecting a relative adjustment between the reader and pattern.

16. In a pattern controlled punch selecting perforating machine, a perforating mechanism, a reader comprising two coöperating members, between which a pattern sheet is arranged to pass, feeding means for the pattern sheet operatively connected to the perforating mechanism, and means independent of the feeding means for effecting a relative longitudinal adjustment between the reader and pattern sheet.

17. In a pattern controlled punch selecting perforating machine, a perforating mechanism, a reader, adapted to coöperate with a pattern sheet, means operatively connected to a moving part of the perforating mechanism for feeding the pattern sheet, and manually operable means for adjusting the reader longitudinally relatively to the pattern sheet.

18. In a pattern controlled punch selecting perforating machine, and in combination, perforating mechanism, a reader, a supporting member therefor, means for feeding a pattern sheet in coöperative relation with said reader, and means for effecting a longitudinal adjustment of the supporting member relative to the pattern sheet.

19. In a pattern controlled punch selecting perforating machine, perforating mechanism, a reader, a support therefor, means for feeding a pattern sheet in coöperative relation with the reader, and means for adjusting the reader in the line of movement of the pattern sheet.

20. In a pattern controlled punch selecting perforating machine, perforating mechanism, a reader, a slidable support therefor, means for feeding a pattern sheet, and manually operable means for adjusting the support and reader in the line of movement of the pattern sheet.

21. In a pattern controlled punch selecting perforating machine, perforating mechanism, a reader, a slidable support therefor, guideways for said support, means for feeding a pattern sheet in coöperative relation with said reader and means for adjusting the support and reader back and forth in said guideways and in the direction of travel of the pattern.

22. In a pattern controlled punch selecting perforating machine, perforating mechanism, a reader, a supporting member therefor, a delivery and a take-up roll for a master sheet arranged respectively on opposite sides of said support member, and means for adjusting said supporting member longitudinally relatively to the line of movement of the master sheet.

23. In a pattern controlled punch selecting perforating machine, and in combination, perforating mechanism, a reader adapted to coöperate with a traveling master, a supporting member for the reader, an adjusting screw having a threaded engagement with said supporting member, and means for rotating said screw to effect an adjustment of the reader in the line of travel of the master.

24. In a pattern controlled punch selecting perforating machine, perforating mechanism, a reader adapted to coöperate with a traveling master, a supporting member for the reader, an adjusting screw having a threaded connection with a part of the supporting member, manually operable means for operating said screw and a delivery and a take-up roll for the master arranged respectively upon opposite sides of the supporting member.

25. In a pattern controlled punch selecting perforating machine, and in combination, perforating mechanism, a reader comprising two coöperating contact members, a support therefor, an adjusting screw in threaded engagement with a part of said supporting member, a rotatable shaft having a gear connection with the screw, and means for feeding a pattern sheet between the two members of the reader.

26. In a pattern controlled punch selecting perforating machine, and in combination, perforating mechanism, a reader comprising two coöperating electric contact members, a supporting element therefor, a screw having a threaded connection with a part of said supporting member, a rotary shaft geared to said screw, a delivery and a take-up roll located respectively upon opposite sides of the supporting member, a pair of feed rolls for a pattern sheet, and means for imparting a step-by-step feed movement to said feed rolls.

27. In a pattern controlled punch selecting perforating machine, the combination with the perforating mechanism, of a reader adapted to coöperate with a traveling pattern sheet, a supporting member for the reader, means for adjusting the supporting member and reader in the line of travel of the pattern, a delivery and a take-up roll for the pattern sheet, a pair of feed rolls, and means operatively connected with a moving part of the perforating mechanism for imparting a step-by-step movement to the feed rolls.

28. In a pattern controlled punch selecting perforating machine, the combination with the perforating mechanism, of a reader adapted to coöperate with a traveling pattern sheet, means operatively connected with the perforating mechanism for imparting a step-by-step feed movement to the pattern, said means comprising a rock shaft having projecting arms, a cam coöoperating with one of

said arms and a connection between the other arm and one of the feed rolls.

29. In a pattern controlled punch selecting perforating machine, and in combination, 5 perforating mechanism, a reader comprising a contact bar and a plurality of coöperating selector fingers, a separate contact member for each finger and a separable interlocking connection between the contact members 10 and fingers to prevent lateral displacement of the latter.

30. In a pattern controlled punch selecting perforating machine, a reader comprising a contact bar and a plurality of coöperating 15 selector fingers, a contact member for each finger having an open seat in its end to receive a free end of each selector finger and prevent lateral displacement thereof.

31. A reader for electrically controlled perforating machines comprising a plurality of selector fingers, a contact member common to all of said fingers and a separate contact plate for each finger, said contact plates each having an open seat in its end to receive 25 a free end of a coöperating finger.

32. A reader for electrically controlled perforating machines comprising a plurality of selector fingers, a contact member common to all of said members, a supporting rail of 30 insulating material for the fingers, a plurality of contact plates each having a recessed end to receive a free end of one of the fingers, and means for supporting the contact plates.

33. A reader for electrically controlled perforating machines comprising a pair of supporting rails of insulating material, a plurality of selector fingers carried by one of 35 said rails, a plurality of contact plates carried by the other rail, each plate having a recess 40 to receive an end of one of the fingers and a contact member common to all of the selector fingers.

34. A reader for electrically controlled perforating machines comprising a plurality 45 of selector fingers, a contact bar common to all of said fingers, a supporting rail for said bar having a face over which a pattern is adapted to travel and means for adjusting the bar relatively to the said face of the supporting rail.

35. A reader for electrically controlled perforating machines comprising a plurality 55 of selector fingers, a channeled supporting rail having a face over which a pattern may travel, a contact member common to all the selector fingers located in said channel, and means for adjusting the contact member

vertically toward and from the upper face of said rail whereby to provide an air space between the ends of the selector fingers and the 60 contact member.

36. A reader of the class described comprising a plurality of selector fingers, a channeled supporting rail over the upper face of which a pattern may travel, a contact member common to all the selector fingers seated in said channel, and means for adjusting the contact member relative to the said upper face of the supporting rail whereby to establish a free space between the contact member and the ends of the selector fingers. 70

37. In a pattern controlled punch selecting perforating machine, a perforating mechanism, a reader, adapted to coöperate with a pattern, and means operated by the punching mechanism for feeding the pattern, said means being manually operable independent 75 of the operation of the perforating machine.

38. In a pattern controlled punch selecting perforating machine, a perforating mechanism, a reader, adapted to coöperate with a pattern, means for feeding the pattern, and means for stopping the operation of the perforating mechanism, said pattern feeding means being manually operable irrespective 80 of the operation of the perforating mechanism. 85

39. In a pattern controlled punch selecting perforating machine, a perforating mechanism, a reader, adapted to coöperate with a pattern, a manually operable pattern feeding means, and means on a movable part of the perforating mechanism for operating the pattern feeding means, said manually operable means being operable irrespective of the 90 operation of the perforating mechanism. 95

40. In a pattern controlled punch selecting perforating machine, perforating mechanism, a reader, adapted to coöperate with a pattern, a manually operable pattern feeding 100 means, and a cam on the main shaft of the perforating mechanism for operating the said pattern feeding means, said manually operable means being operable irrespective of the 105 operation of the perforating mechanism.

In testimony whereof we have hereunto set our hands in the presence of two subscribing witnesses.

G. HOWLETT DAVIS.
